Primary Examiner — Elizabeth J Oswecki*(74) Attorney, Agent, or Firm* — Michael Best and Friedrich LLP(57) **CLAIM**

The ornamental design for a semiconductor device, as shown and described.

DESCRIPTION

FIG. 1 is a front, top, right perspective view of a semiconductor device showing my new design; FIG. 2 is a front, bottom, right perspective view thereof; and, FIG. 3 is a front elevational view thereof.

FIG. 4 is an enlarged front, top, right perspective view taken along lines 4-4 in FIG. 1; and,

FIG. 5 is an enlarged front elevational view taken along lines 5-5 in FIG. 3.

The shaded surfaces areas on the semiconductor device define the claimed design. The broken lines shown in the drawings represent portions of the semiconductor device that form no part of the claimed design. The dashed-dot-dashed lines form the boundary lines of the claimed design and form no part of the claimed design. All surfaces not shown form no part of the claimed design.

1 Claim, 5 Drawing Sheets(56)
